(57) **CLAIM**

The ornamental design for a security system control panel with touchscreen interface, as shown and described.

DESCRIPTION

FIG. 1 is a perspective view of the security system control panel with touchscreen interface.

FIG. 2 is a front elevation view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a rear elevation view thereof.

FIG. 8 is a rear perspective view thereof shown in a second state; and,

FIG. 9 is a left side elevation view thereof.

The broken lines in the drawings depict portions of the security system control panel with touchscreen interface in which the design is embodied that form no part of the claimed design.
